Attorney

UNITED STATES PATENT OFFICE.

ADAM LEONODES CRANE, OF FORT MILL, SOUTH CAROLINA.

CEMENT TIE AND RAIL-FASTENER.

1,373,601.

Specification of Letters Patent.

Patented Apr. 5, 1921.

Application filed November 22, 1920. Serial No. 425,797.

To all whom it may concern:

Be it known that I, ADAM LEONODES CRANE, a citizen of the United States, residing at Fort Mill, in the county of York and 5 State of South Carolina, have invented certain new and useful Improvements in Cement Ties and Rail-Fasteners, of which the following is a specification, reference being had to the accompanying drawings.

10 Cement or concrete ties have been heretofore used, but they have not been a success, as they include no means for more or less cushioning the rail, for the reason that the rails either rest directly upon the cement or 15 concrete, or upon plates.

The main purpose of the present invention is to provide a cement or concrete tie, wherein in the rails are cushioned, thereby eliminating a rigid support for the rails.

20 In order to cushion the rails the tie includes wooden insert blocks, which are removably dovetailed in the tie, and are supported upon a steel, iron, or other metal plate, so as to prevent the wooden insert 25 blocks from contacting direct with the cement, and tending to more or less crush it.

Owing to the insert wooden blocks being removable when worn, and owing to the body of the tie being of cement, the tie is 30 very durable, and will last substantially indefinitely, for when the blocks are worn they may be easily replaced with new ones.

Further more the tie of this character is very simple and can be easily constructed 35 for a relatively low cost and sold at a reasonable profit.

As a further purpose the invention aims to provide fastening means for the rails, in combination with means connecting the fastening means, in order to prevent the rails from spreading.

Still another purpose resides in the provision of means co-operating with the fasteners for the rails, to prevent the bolts 45 which hold the rail securing plates in position, from pulling through the cement or concrete, and also preventing it from crumbling or breaking.

An additional purpose is the provision of 50 plates resting upon the insert wooden blocks, to prevent the rails from cutting into the blocks.

It will be noted that the plate supporting the wooden insert blocks tends to add strength and durability to the tie, and at the 55 same time to reinforce the tie as a supporting base for the rails.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what 65 is claimed.

The invention comprises further features and combination of parts, as will be herein-after set forth, shown in the drawings and 70 claimed.

In the drawings:

Figure 1 is a perspective view of the improved tie constructed in accordance with the invention, showing the rails mounted thereon, and illustrating the fastening 75 means for the rails and the insert wooden blocks.

Fig. 2 is a sectional view on line 2—2 of Fig. 1.

Fig. 3 is a cross sectional view on line 3—3 80 of Fig. 1.

Fig. 4 is a bottom plan view of the tie showing the plates embedded in the under-face thereof.

Referring more especially to the drawings, 1 designates an improved tie, which may be constructed of any suitable plastic material preferably cement or concrete, and in constructing this tie, it is provided with transversely disposed dovetail recesses 2, the 85 end walls of which converge upwardly as shown. To be removably mounted in the dovetail recesses are wooden insert blocks 3, the ends of which converge upwardly correspondingly to and engaging the end walls of 95 the recesses, thereby preventing movement of the insert blocks longitudinally of the tie.

In constructing the tie, a steel, iron or other metal plate 4 is embedded in the tie, and is so arranged adjacent the recesses, as 100 to form the bottoms of the recesses, and to constitute seats 5 for the insert wooden blocks. It will be noted that the ends of this plate 4 extend beyond the remote end

walls of the recesses, thereby more securely holding the plate in place, and at the same time permitting the insert wooden blocks to engage therewith. It will be noted that this 5 plate is disposed so that its upper face will assume a position slightly above the concrete or cement, at points designated by the character 6, so that the insert wooden block will rest entirely upon the plate. The distance 10 of the upper surface of the plate above the concrete of the tie, in practice, is hardly perceptible to the eye, nevertheless a space exists.

When the tie is in use and the insert 15 blocks are arranged in their recesses, the plate 4 is entirely hidden.

Engaging the insert wooden blocks are metallic plates 7, on which the rails 8 are supported.

20 Countersunk in the undersurface of the tie are metallic plates 9, through which, the tie, the plate 4 and plates 7 are the elongated bolts 10. These bolts also pass upwardly through the insert wooden blocks. 25 The plates 9 are countersunk in the undersurface of the tie sufficiently so that the heads of the bolts will not contact or engage upon the ballast or road bed, thereby permitting the tie to be evenly supported in 30 position.

Rail fastening plates 11 are provided, and are engaged with the plates 7. These rail fastening plates are arranged in diagonally opposite positions relatively to each other 35 upon opposite sides of each rail. The plates 11 are cutaway on their undersurfaces, to overlie the bases of the rails. Furthermore these rail fastening plates are disposed relatively to each other, so that when mounting 40 a rail, it may be disposed on an angle, so that its base may engage between the rail holding plates. The bolts 10 have their upper ends also engaging through the rail securing plates, there being nuts applied to 45 the bolts, for holding the various parts together and in position. The plates 9 which are countersunk in the undersurface of the tie are arranged in relative inclined positions, so that the bolts 10 (which are diagonally disposed) may pass through the plates 9, tie and the plates 4, 7 and 11, thereby producing a rigid and secure holding means for the rails, and at the same time strengthening the tie.

50 As previously stated the bolts 10 are sufficiently relatively spaced, so as to permit the rail to be inserted between the plates 11 on an angle, so that afterward the rails may be disposed in their proper positions trans-

versely of the tie. This may be accomplished by not removing either one of the holding or securing plates 11, though it is obvious that such plates may be removed, for the reason that the rails may be spaced 55 in their proper positions. The upper ends

of bolts 10 have nuts thereon, to hold the rail fastening plates in position.

The metal plates 7 are provided with shoulders 11^a, which are engaged by the outer edges of the bases of the rails, thereby assisting materially in preventing the 70 rails from spreading.

The plates 7 are provided with upstanding projections 4^a, adapted to pierce into the wooden insert blocks 3, thereby acting to 75 hold the same in place.

The invention having been set forth, what is claimed as being useful is:—

1. In a tie, a plastic tie body having dovetail-recesses in its upper face, insert wooden 80 blocks removably dovetailed in said recesses, plates resting upon the blocks, rails engaging said plates, rail fastening plates diagonally disposed on opposite sides of the rails, and bolts passing upwardly through the 85 blocks and the rail supporting and fastening plates to hold said parts in position, a metallic plate embedded in the tie body and having its upper face forming the bottom of the recesses and constituting a bed for the 90 insert blocks.

2. In a tie, a plastic tie body having dovetail recesses in its upper face, insert wooden blocks removably dovetailed in said recesses, 95 plates resting upon the blocks, rails engaging said plates, rail fastening plates diagonally disposed on opposite sides of the rails, and bolts passing upwardly through the blocks and the rail supporting and fastening plates to hold said parts in position, a metallic plate embedded in the tie body and having its upper face forming the bottom of the 100 recesses and constituting a bed for the insert blocks, said embedded plate having its upper face disposed a short distance above 105 the plastic material of the bottoms of the recesses, and plates countersunk in the undersurface of the tie to be engaged by the bolts, to prevent the bolts from pulling through the 110 body of the tie.

3. In a tie, a plastic tie body having dovetail recesses in its upper face, a metallic elongated plate relatively narrower than the width of the tie and embedded therein and adjacent said recesses, whereby it forms 115 largely the bottoms of said recesses, the ends of said plate extending beyond the remote walls of the recesses, insert blocks in said dovetail recesses and resting upon the plate, plates resting upon the insert blocks, and 120 means passing outwardly through the tie and through the insert blocks and the plates thereon and including means engaging with the rails to hold them in position.

4. In a cement tie, a plastic tie having 125 dovetail recesses, a single elongated flat plate embedded in the tie and bridging from under one recess to and under the opposite recess, said plate constituting largely the bottoms of the recesses, insert wooden 130

blocks in said recesses and resting upon the metallic bottoms of the recesses, said metallic bottoms of the recesses being relatively higher than the bottoms at the open ends of 5 said recesses, thereby supporting the insert blocks in raised positions out of engagement with the bottoms of the recesses at their open

ends, and means passing through the tie and the insert blocks and including means connected with the rails for holding them in 10 place.

In testimony whereof I hereunto affix my signature.

ADAM LEONODES CRANE.
